(57) **CLAIM**

The ornamental design for a tire, as shown and described.

DESCRIPTION

FIG. 1 is a side perspective view of a tire showing my new design, it being understood that the tread pattern is repeated throughout the circumference of the tire, the opposite side being the same as that shown;

FIG. 2 is a front elevational view of the tire;

FIG. 3 is a side elevational view of the left side of the tire;

FIG. 4 is a side elevational view of the right side of the tire;

FIG. 5 is an enlarged fragmentary view of FIG. 2 with section lines related to views 6-6, 7-7, 8-8, and 9-9;

FIG. 6 is a first transversal section view of the tire taken along line 6-6;

FIG. 7 is a second transversal section view of the tire taken along line 7-7;

FIG. 8 is a third transversal section view of the tire taken along line 8-8; and,

FIG. 9 is a fourth transversal section view of the tire taken along line 9-9.

The broken lines depict environmental subject matter that forms no part of the claimed design.
